FLUID PUMP AND MOTOR

Alfons H. Neuland, Cleveland, Ohio

Application September 20, 1941, Serial No. 411,649

9 Claims. (Cl. 103—117)

This invention relates to expandible chamber fluid motors and pumps of the kind having rotatable displacement elements and chambers and its general object is to provide a device of simple construction wherein the stroke of the displacement elements may be varied and reversed and which lends itself to rapid production at low cost.

A particular object of the invention is to provide a variable or reversible stroke device of relatively simple construction in which the pressure is substantially balanced and which may be operated with high pressure and at high speed.

My invention resides in novel features of construction and in the arrangement and combination of its component parts. The foregoing and other objects and advantages will appear in the following description and from the drawings and my invention will hereafter be more fully defined in the appended claims.

Fig. 1 is a vertical section of a balanced pressure fluid motor or pump embodying my invention.

Fig. 2 is a horizontal section through the device shown in Fig. 1.

Fig. 3 is a transverse view of the device, taken on the line A—A of Fig. 2, showing particularly the circumferential arrangement of the displacement elements and rotor separators.

Fig. 4 is a vertical view, partly in section, of a modified form of balanced pressure pump or motor.

Fig. 5 is a right end view of the separable rotor of the device in Fig. 4, with the right end portion removed in the upper half.

Fig. 6 is a vertical view, partly in section, of another modified form of pump or motor.

In the following description my device will be referred to as a pump, although it will be understood that it is capable of operating as a motor when supplied with fluid under pressure.

The pump shown in Figures 1 to 3 consists of a rotatable separator element or rotor having a power connection 11, a pair of journal portions 12, 12' and a plurality of laterally extending arcuate separators 13, 13' provided with bosses or shoulders 14, 14' and shaped to form axially concentric inner concavely spherical surfaces 15, 15' and to form outer convexly spherical surfaces 16, 16' spherically parallel or concentric with said inner spherical surfaces and between separators to form arcuate and laterally concentric working or driving surfaces 17. I provide a rotatable inner closure element 18 within the rotor provided with a preferably integrally formed, central fulcrum or control shaft 19 extending out of the ro-

tor and provided with a plurality of driving projections or pins 20, also preferably integrally formed, extending outwardly into the spaces between separators and arranged in a plane perpendicular to its axis of rotation. The inner element 18 is further provided with an axially concentric convexly spherical surface in operatively liquid tight closure relation with the inner spherical surfaces of the separators 13, 13' adapted to move therebetween in any direction. I provide outer closure means for the rotor comprising intermediate portions 21, 21' having concavely spherical surfaces associated in closure relation with the outer surfaces of separators 13, 13' and forming with the separators and the inner element a plurality of pairs of quadrangularly sectioned laterally, extending and concentrically aligned displacement chambers 22, 22' having spherically parallel inner and outer surfaces and having openings 23, 23' in the outer faces of the rotor formed by the ends of the separators and the intermediate closure portions 21, 21'. The rotor is separable in a plane perpendicular to its axis of rotation and its portions are joined together with each other and with the intermediate closure portions 21, 21' by means of the shoulders 14, 14' and the bolts 24 locking the parts firmly together to rotate as a unit. The outer closure means further comprises a stationary portion 25 arranged on one outer side of the intermediate portions and another stationary portion 25' arranged on the other outer side of the intermediate portions and is joined with the first mentioned stationary portion by bolts 26 to form therewith a pump or motor housing. The stationary housing portions are provided with valve faces preferably formed by plates 27, 27' of wear resisting material spaced from one another to provide close working clearances between valve 40 and rotor faces, and are each provided with diagonally opposite inlet ports 28, 28' and with diagonally opposite outlet ports 29, 29' for conducting fluid into and out of both sides of the pump as shown by the arrows. The inlets and outlets may be joined externally or they may be joined in the housing as hereinafter described in connection with Fig. 4. The rotor is operatively supported in the housing preferably by anti-friction means such as the needle bearings 30, 30', bearing against the rotor journals 12, 12'. I further provide double acting driving displacement elements 31 engaging the working surfaces between adjacent separators having spherically concentric inner and outer surfaces in operatively liquid tight relation with the inner closure

element 18 and with the outer closure elements 21, 21'. The displacement elements, because of the concentrically parallel section of the displacement chambers are free to move therein arcuately and are arranged to engage the driving projections or pins 20, preferably in operative bearing relation therewith to provide pivotable and successively engaging driving connections between the rotor and inner element 18 and at the same time are in effect caused to reciprocate within the displacement chambers during rotation of the rotor and angular displacement of the axis of the inner element with respect to the rotational axis of the rotor. In this connection it should be noted that because of the arrangement of the axis of pins 20 on the inner element in a plane perpendicular to its rotational axis and centrally with respect to its spherical surface, the control shaft 19 may be angularly displaced to provide a substantial stroke with only a slight circumferential displacement of the displacement elements with respect to the chambers, the working clearance between chambers and pins and the displacement elements being adequate to permit such slight circumferential displacement. The intermediate closure portions 21, 21' also serve to provide a thrust bearing surface for the displacement elements 31 which, during rotation, because of centrifugal force, are forced outwardly against the surfaces and from Fig. 1 it will be seen that the elements 31, even during conditions of maximum stroke, bridge the central intervening space and at all times engage both intermediate portions 21, 21'. With this construction and arrangement the rotational friction is substantially confined to that between the rotor and valve faces, relative movement and friction between displacement elements and chambers and between the rotor and inner element being proportional only to the stroke of elements 31, making it possible to secure a relatively high efficiency especially during operation at high speed with a small stroke.

The device is provided with means for angularly displacing the rotational axis of inner element 18 in a fulcrum plane with respect to the rotor axis, that is in a plane centrally between the fluid inlet and outlet ports shown particularly in Fig. 2, in which it is seen that the control shaft 19 has been shifted forward in a horizontal plane and that the plane of displacement occupies a central position between the ports 28' and 29'. This means comprises a fulcrum roller 32 operatively mounted on the fulcrum shaft 19, preferably by anti-friction means, such as the rolling bodies 33 and rollingly engages one or the other fulcrum surfaces 34, 35 provided in the stationary housing portion 25', and further comprises a control bearing also preferably provided with rolling bodies 36 which may be arranged to operate within a raceway 37 having a spherical bearing surface permitting angular movement of the shaft 19 with respect to the control element 38 which is slidably supported by the housing portion 25'. The control shaft 19 is thus free to move in the fulcrum plane with but little friction and may be shifted to various positions by suitable means connected to the rod 39; or it may be shifted by some means such as fluid pressure applied to the cylinder 40 which may be balanced by a spring 41, particularly in instances where the cylinder 40 is connected with outlet port 28 or 29' to provide a substantially constant pumping pressure. While the rotor shown in Figures 1 to 3 is constructed to provide

six displacement chambers, I may construct the rotor to provide a larger or smaller number of chambers depending on the characteristics it is desired to secure.

When driven as a pump in the direction indicated by the arrow and the control shaft shifted upwardly as shown in Fig. 2, the displacement elements reciprocate so as to develop suction at the inlet ports 28, 28' and to develop pressure in the diagonally opposite outlet ports 29, 29'. The lateral thrust exerted on the rotor by pressure in port 29 is opposed and substantially balanced by the lateral thrust exerted on the rotor by pressure in the port 29', which makes it possible for the rotor to float between the valve faces 21, 21' without exerting any thrust thereon, the tendency of the rotor to skew counterclockwise in an axial plane, upwardly at the right and downwardly at the left being taken care of by the roller bearings 30, 30' respectively. Pressure thrust on the intermediate and inner closure elements 21, 21' and 18 is similarly balanced since thrust on the area exposed to pressure on one side is equalized by a similar thrust on the area exposed to pressure on a diagonally opposite side, permitting the inner element to float within the rotor without imposing any substantial load upon the spherical bearing surfaces. The diagonally opposite pressures on the displacement elements 31 also operate to neutralize one another with respect to load between the spherical surfaces of the inner element and rotor but develop a skewing movement in the fulcrum plane, which however is taken by the fulcrum shaft 19 and transferred to the housing through the roller 32 as heretofore already described. When the device is to be operated with a fixed stroke, the control elements may be omitted and the necessary fulcrum provided by mounting a bearing race equivalent to the roller 32 directly in the housing so as to operatively support the fulcrum shaft 19 in an inclined position such as shown in the drawings. Because of the balanced pressure between the rotor and inner and outer closure elements, the device may be operated under high pressure without risk of seizure between operatively associated surfaces. However it will be noted that each side of the device constitutes an operable unit and, if desired, the two sides may be connected to separate circuits or one side may be operated to the exclusion of the other side. In the latter instance the housing portion 25' serves to take the pressure thrust from the rotatable elements.

Two or more devices may be connected with one another to form the pump and motor units in a power transmission or control system. In such an application the pump unit may be driven at a constant speed through the power connection 40, and the speed and direction of rotation of the motor may be varied and reversed respectively by movement of the control shaft 19 of the pump unit into various positions. When the pump shaft 19 is driven in the direction shown by the arrow and the control shaft is moved upwardly, as shown in Fig. 2, fluid is forced out of the ports 29, 29' and, flowing into the motor connected to these ports, drives the motor in a given direction and as the pump shaft 19 is moved downwardly, the pump output and motor speed decrease until the pump shaft 19 reaches a central position, when the pump output and motor speed reach zero. When the downward movement of the pump shaft 19 is continued beyond the central position, the pumping pressure and liquid

flow are reversed. Fluid is now forced out of the ports 28, 28' and drives the motor in reverse direction. Thus the units may be permanently connected and the speed and direction of the motor varied and reversed in response merely to movement of the pump control shaft.

In the modification shown in Figures 4 and 5, the stationary housing portions 25, 25' are shaped to form a concavely spherical surface providing the outer closure for the displacement chambers 22, 22', the spherical surface being extended toward the axis of the rotor to form spherical valve faces and a pair of diagonally opposite inlet ports and a pair of diagonally opposite outlet ports arranged in a horizontal plane in Fig. 4, their axial position with respect to the rotor being indicated by the dotted lines 42, 43. The outer convexly spherical surfaces of the rotor separators 13 are also extended to provide openings therein for the displacement chambers which cooperate with the valve faces to conduct fluid into and out of the chambers. The extended spherical surfaces beyond the separators further provide bearings operatively supporting the rotor within the housing, the roller bearing 30 serving to maintain the axial position of the rotor and to take the load due to the tendency of the rotor to skew in a plane at right angles to the fulcrum plane. The housing may be modified to provide ducts whereby a portion of the fluid entering the inlet pipe 44 flows downwardly to the inlet port on the far side and another portion flows axially through a thin sealing tube 45 and thence downwardly to the inlet port on the near side as shown by the arrows. Similar ducts are provided for conducting fluid out of the device, fluid from the outlet port on the near right side flowing through the sealing tube 46 into outlet pipe 47 and being joined by fluid from the outlet port on the far left side. The axially separable portions of the rotor are joined with one another by suitable means, such as the screws 48, imbedded directly in the separators 13, 13'. The concentrically parallel working surfaces of the displacement spaces 13 in the rotor may be formed by radially diverging surfaces as in Fig. 3, or they may be formed by equidistant surfaces as in Fig. 5 to facilitate manufacture of the rotor and displacement elements, the inner and outer surfaces of the displacement elements being provided with spherical surfaces as in Fig. 3. The modification shown in Fig. 4 operates, and the pressures therein balance one another in a manner similar to that described in connection with Figures 1 to 3, however the separators 13, 13' forming the displacement chambers move relatively with respect to the housing in proportion to the speed of rotation involving a considerable frictional loss which is further increased by the rotational rubbing friction of the displacement elements with respect to the housing due to centrifugal force as a result of which it is incapable of attaining the efficiency or operating at high speed such as are possible with the device in Figures 1 to 3.

The modification shown in Fig. 6 is similar to the device in Figures 4 and 5 in that the stationary housing portions 25, 25' provide the spherical closure for the rotor but differs therefrom in that it is provided with but a single pair of ports and ducts arranged in a horizontal plane, the outline of which is indicated in a vertical plane in Fig. 6 by the dotted lines 49, 50. The separators 13 are shaped to extend beyond the center of their spherical surface and provide the working surfaces for all positions of displacement

elements 31. The rotor is held in operative contact with inner element 18 and housing portion 25 by the convexly spherical surface 51 on the housing element 25' in operative bearing contact with the spherical surface of the inner element 18, which also serves to take the pressure thrust on the rotatable elements. In this modification the pressure between operatively associated parts is not balanced as in the devices shown in Figures 1 to 5, nor has it the low friction loss and high efficiency of the device shown in Figures 1 to 3, but is suitable for operation with a moderate speed and pressure and provides a rugged variable output device that can be manufactured at low cost.

Having thus described my invention what I claim as new and desire to secure by Letters Patent is:

1. In a fluid motor or pump, the combination of a rotor having a journal end portion providing a power connection and having a plurality of circumferentially spaced laterally extending arcuate separators formed integral with said end portion and shaped to provide concentric with each other and with the rotational rotor axis inner and outer spherical surfaces and between adjacent separators to provide arcuate working surfaces; a rotatable inner closure element having a convexly spherical surface in operative closure relation with the inner surface of said separators adapted to rotate on an axis angularly displaced with respect to the rotational axis of said rotor and provided with a plurality of projections extending outwardly between said separators; an outer closure element having a concavely spherical surface in closure relation with the outer surface of said separators forming therewith and with said inner closure element a plurality of quadrangular laterally extending displacement chambers between separators having spherically parallel inner and outer surfaces; means for rotationally supporting said rotor and said inner element on axes angularly displaced one with respect to the other; and a plurality of quadrangularly sectioned arcuate displacement elements fitted within said displacement chambers in operatively liquid-tight relation therewith and pivotally supported by said projections on axes perpendicular to the spherical surface of the inner element engaging said working surfaces and providing a driving connection between one of the separators and the inner element.

2. A fluid motor or pump comprising in combination a rotor having a journal end portion providing a power connection and having a plurality of circumferentially spaced laterally extending arcuate separators formed integral with said end portion and shaped to provide concentric with each other and with the rotational rotor axis inner and outer spherical surfaces and between adjacent separators to provide arcuate working surfaces; a rotatable inner closure element having a convexly spherical surface in operative closure relation with the inner surface of said separators adapted to rotate on an axis angularly displaced with respect to the rotational axis of said rotor and provided with a plurality of projections extending outwardly between said separators; a stationary housing shaped to provide an outer closure portion having a convexly spherical surface in operative closure relation with the outerly spherical surface of said separators forming therewith and with said inner closure element a plurality of quadrangular laterally extending arcuate displacement chambers having

spherically parallel inner and outer surfaces and further shaped to provide inlet and outlet ports registering with said displacement chambers, the housing being provided with means for rotationally supporting the rotor and the inner closure element on axes angularly displaced one with respect to the other; and a plurality of quadrangularly sectioned arcuate displacement elements operatively fitted within said displacement chambers in operatively liquid-tight relation therewith and pivotally supported by said projections on axes perpendicular to the spherical surface of said inner element engaging said working surfaces and providing a driving connection between one of the separators and the inner element.

3. A fluid motor or pump comprising in combination a rotor having a pair of axially separable journal end portions, each end portion having a plurality of circumferentially spaced laterally extending arcuate separators formed integral therewith provided with means for joining the portions together and shaped to provide concentric with each other and with the rotational rotor axis inner and outer spherical surfaces and between adjacent separators to provide arcuate working surfaces; a rotatable inner closure element having a convexly spherical surface in operative closure relation with the inner surface of said separators adapted to rotate with but on an axis angularly displaced with respect to the rotational axis of said rotor and provided with a plurality of projections extending outwardly between said separators; a stationary housing shaped to provide a central closure portion having a concavely spherical surface in operative closure relation with the outerly surface of said separators forming therewith and with said inner closure element a plurality of quadrangular laterally extending arcuate displacement chambers having spherically parallel inner and outer surfaces and further shaped to provide diagonally opposite inlet and diagonally opposite outlet ports positioned to register with said displacement chambers and provided with means for rotationally supporting the rotor and the inner closure element on axes angularly displaced one with respect to the other; and a plurality of quadrangularly sectioned arcuate displacement elements operatively fitted within said displacement chambers in operatively liquid-tight relation therewith and pivotally supported by said projections on axes perpendicular to the spherical surface of said inner element engaging said working surfaces and providing a driving connection between one of the separators and the inner element.

4. A fluid motor or pump comprising in combination a rotor having a journal end portion providing a power connection and having a plurality of circumferentially spaced laterally extending arcuate separators formed integral with said end portion and shaped to provide concentric with each other and with the rotational rotor axis inner and outer spherical surfaces and between adjacent separators to provide arcuate working surfaces, said arcuate separators being formed to extend laterally substantially beyond the center of said spherical surfaces; a rotatable inner closure element having a convexly spherical surface in operative closure relation with the inner surface of said separators adapted to rotate on an axis angularly displaced with respect to the rotational axis of said rotor and provided with a plurality of projections extending outwardly between said separators; a stationary

housing shaped to provide an outer closure having a concavely spherical surface in operative closure relation with the outerly surface of said separators forming therewith and with said inner closure element a plurality of quadrangular laterally extending arcuate displacement chambers having spherically parallel inner and outer surfaces and further shaped to provide inlet and outlet ports registering with said displacement chambers, the housing being provided with means for rotationally supporting the rotor and the inner closure element on axes angularly displaced one with respect to the other; and a plurality of quadrangularly sectioned arcuate displacement elements operatively fitted within said displacement chambers in operatively liquid-tight relation therewith and pivotally supported by said projections on axes substantially perpendicular to the spherical surface of said inner element engaging said working surfaces and providing a driving connection between one of the separators and the inner element.

5. A fluid motor or pump comprising in combination a rotor having a pair of axially separable journal end portions, each end portion having a plurality of circumferentially spaced laterally extending arcuate separators formed integral therewith provided at their free ends with outwardly extending shoulders for joining the portions together and shaped to provide concentric with each other and with the rotational rotor axis inner and outer spherical surfaces and between adjacent separators to provide arcuate working surfaces, said rotor further including an outer closure portion for each of said separable rotor portions having a concavely spherical surface associated with the outer surface of corresponding separators and positioned thereon to provide outwardly facing fluid openings between separators positioned between each outer closure portion and a corresponding end portion and further including means for locking the separable end portions with each other and with said outer closure portions to form a rotor unit; a rotatable inner closure element having a convexly spherical surface in operative closure relation with the inner surface of said separators adapted to rotate with but on an axis angularly displaced with respect to the rotational axis of said rotor forming with the rotor unit a plurality of quadrangularly sectioned laterally extending arcuate pairs of displacement chambers having spherically parallel inner and outer surfaces and provided with a plurality of projections extending outwardly between said separators; a stationary housing for said rotor provided with fluid inlet and outlet ports registering with the fluid openings in said rotor and provided with means for rotationally supporting the rotor and the inner element on axes angularly displaced one with respect to the other; and a plurality of quadrangularly sectioned arcuate displacement elements operatively fitted within said pairs of displacement chambers in operatively liquid-tight relation therewith and pivotally supported by said projections on an axis substantially perpendicular to the rotational axis of the inner closure element engaging said working surfaces and providing a driving connection between one of the separators and the inner element.

6. In a fluid motor or pump, the combination of a rotor including a pair of axially separable portions each portion having a plurality of circumferentially spaced laterally arcuate separators provided with means for joining the por-

tions together and shaped to provide concentric with each other and with the rotor axis inner and outer spherical surfaces and between adjacent separators to provide arcuate working surfaces; a rotatable inner closure element having a convexly spherical axially concentric surface in closure relation with the inner surface of said separators; an outer closure element having a concavely spherical surface in closure relation with the outer surface of said separators forming therewith and with said inner closure element a plurality of quadrangular laterally arcuate displacement chambers having spherically parallel inner and outer surfaces; a plurality of displacement elements operatively fitted within said displacement chambers and pivotally supported by said inner element on an axis perpendicular to its spherical surface; and means for operatively supporting said inner element on an axis angularly displaced with respect to the rotational axis of said rotor thereby causing arcuately lateral reciprocation of the displacement elements within said chambers.

7. In a variable stroke fluid motor or pump, the combination of a rotor having a plurality of circumferentially spaced laterally arcuate separators shaped to provide concentric with each other and with the rotor axis inner and outer spherical surfaces and between adjacent separators to provide arcuate working surfaces; inner and outer closure elements having spherical surfaces in closure relation with the spherical surfaces of said separators and forming therewith a plurality of quadrangular laterally arcuate displacement chambers having spherically concentric inner and outer surfaces, one of said closure elements being provided with projections extending radially into said chambers; a plurality of displacement elements fitted within said displacement chambers in operatively liquid-tight relation therewith and pivotally supported by said projections, one of said displacement elements providing a pivoted driving connection between a corresponding projection and said rotor; and means for variously angularly displacing the rotational axis of the last mentioned closure element with respect to the rotational axis of the rotor thereby causing arcuately lateral reciprocations of the displacement elements within said chambers and causing the stroke of such reciprocations to vary in response to variations in the angular displacement between said rotational axes.

8. In a variable stroke fluid motor or pump, the combination of a rotor having a plurality of circumferentially spaced laterally arcuate separators shaped to provide concentric with each other and with the rotor axis inner and outer

spherical surfaces and between adjacent separators to provide arcuate working surfaces; a rotatable inner closure element having a convexly spherical surface in closure relation with the inner surface of said separators; an outer closure element having a concavely spherical surface in closure relation with the outer surface of said separators forming therewith and with said inner closure element a plurality of quadrangular laterally arcuate displacement chambers having spherically parallel inner and outer surfaces; a plurality of displacement elements operatively fitted within said displacement chambers in operatively liquid-tight relation therewith and pivotally supported by said inner element, one of said displacement elements providing a pivoted driving connection between a corresponding separator and the inner element; and means for variously angularly displacing the rotational axis of said inner element with respect to the rotational axis of said rotor thereby causing arcuately lateral reciprocation of the displacement elements within said chambers and causing the stroke of such reciprocation to vary in response to variations in the angular displacement between said rotational axes.

9. In a variable stroke fluid motor or pump, the combination of a rotor having a plurality of circumferentially spaced laterally arcuate separators shaped to provide concentric with each other and with the rotor axis inner and outer spherical surfaces and between adjacent separators to provide arcuate working surfaces; a rotatable inner closure element having a convexly spherical surface in closure relation with the inner surface of said separators and provided with a plurality of spaced outwardly extending pivots arranged perpendicular to its spherical surface; an outer closure element having a concavely spherical surface in closure relation with said outer surface of said separators forming therewith and with said inner closure element a plurality of quadrangular laterally arcuate displacement chambers; a plurality of arcuate displacement elements engaging said pivots fitted and adapted to arcuately reciprocate within said displacement chambers of said displacement elements providing a driving connection between the inner element and the rotor; and means for variously angularly displacing the rotational axis of the inner element with respect to the rotational axis of said rotor thereby causing arcuately lateral reciprocation of the displacement elements within said chambers and causing the stroke of such reciprocation to vary in response to variations in the angular displacement between said rotational axes.

ALFONS H. NEULAND.
